Houdaille-Hershey Corporation, Detroit, Mich.,
a corporation of Michigan

Application July 19, 1941, Serial No. 403,134

8 Claims. (Cl. 62—126)

This invention relates to heat exchangers and more particularly to sheet metal evaporator units having laterally extending plates substantially identical with shelves provided therein.

According to this invention there is now provided a U-shaped evaporator unit composed of secured-together embossed metal sheets defining header chambers and refrigerant flow passageways therebetween. The unit has a sheet metal refrigerated shelf spanning the legs of the U. A plate or wall also extends laterally outward from the top of one of the legs of the U-shaped member. This wall and the shelf are composed of embossed secured-together metal sheets defining a refrigerant flow passageway therebetween and one of the features of this invention includes duplication of structure in the wall and in the shelf so that only one set of forming dies need be used to make both members. If desired the wall member can be somewhat larger than the shelf member but a mere trimming of the wall member adapts it for use as a shelf.

Another feature of the invention resides in the provision of but a single inlet and a single outlet for the evaporator units while at the same time effecting refrigerant flow through the laterally extending wall, the shelf, and the U-shaped unit.

It is, then, an object of this invention to provide sheet metal heat exchangers having a plurality of substantially identical parts.

A further object of this invention is to provide U-shaped sheet metal evaporator units having refrigerated shelves spanning the legs thereof together with laterally extending walls of the same construction as the shelves.

A further and specific object of this invention is to provide U-shaped sheet metal evaporator units with a laterally extending flat wall carried by one leg of the unit and a shelf bridging both legs of the unit and having the same construction as the wall.

Another limited object of this invention is to provide a U-shaped sheet metal evaporator unit having a refrigerated shelf bridging the legs of the U, and a flat refrigerated wall extending laterally from one leg of the U, with refrigerant conducting tubes joining the wall with the shelf and also joining the shelf with the U-shaped unit proper whereby only one refrigerant inlet and one refrigerant outlet are necessary for flowing refrigerant through the wall, the shelf and the U-shaped unit.

Other and further objects of this invention will become apparent to those skilled in the art from the following detailed descriptions of the

annexed sheets of drawings, which by way of preferred examples, illustrate one embodiment of the invention.

It should be understood that the invention is not limited to the single preferred embodiment shown on the drawings but includes many other embodiments within its scope.

On the drawings:

Figure 1 is a top plan view of an evaporator unit according to this invention.

Figure 2 is a front end elevational view of the unit shown in Figure 1.

Figure 3 is a side elevational view of the unit shown in Figures 1 and 2.

Figure 4 is an isometric view of the laterally extending flat wall for the unit illustrating, in dotted lines, the manner in which this wall can be converted into a shelf.

Figure 5 is an end elevational view showing a shelf formed from the wall illustrated in Figure 4.

As shown on the drawings:

In Figures 1 to 3, inclusive, the reference numeral 10 designates generally an evaporator unit according to this invention composed of a U-shaped part 11, a refrigerated shelf 12 bridging the legs of the U-shaped part 11, and a laterally extending refrigerated part 13 secured to one of the legs of the U-shaped part.

The U-shaped part 11 is composed of brazed or welded-together inner and outer metal sheets 14 and 15 respectively. The outer metal sheet 15 is embossed with a plurality of flutes 16 providing refrigerant-circulating ducts. Both the inner and the outer sheets are further embossed to provide a pair of cylindrical headers 17 defining chambers communicating with the ducts provided by the flute 16. These headers 17 are positioned in the legs of the U part 11 in spaced relation from the top ends of the legs. The sheets 14 and 15 are further embossed to provide an upper header 18 in each leg of the U-shaped part 11. The inner sheet 14 is embossed as at 19 to provide passageways connecting the chambers in the headers 17 and 18 of each leg.

The rear end of each top header 18 communicates with a duct provided by a flute 20 embossed in the outer sheet 15. This flute 20 provides an exhaust passageway for removing spent refrigerant from the top headers and extends around the sides of the U-shaped part 11 into communication with a duct provided by a flute 21 on the inner sheet 14 at the bottom of the U-shaped part. This duct defined by the flute 21 receives an exhaust tube 22 adapted for connec-

tion with the suction line to the compressor in a mechanical refrigeration system.

The bottom of the outer sheet 15 is embossed to provide a longitudinal inlet flute 23 communicating with each of the refrigerant expansion ducts provided by the flutes 16. The rear end of this flute 23 receives a tube 24 supplying refrigerant to the circulating ducts in the flutes 16 from the shelf part 12.

The U-shaped part 11 thus has side walls and a bottom enclosing a sharp freezing space 25 which contains the shelf part 12 therein. The upper ends of the side walls of the U-shaped part 11 are turned horizontally inward to provide flanges 26 for a purpose to be more fully hereinafter described.

The shelf part 12 is composed of a top metal sheet 30 and a bottom metal sheet 31 embossed to provide a flute 32 defining a serpentine duct for refrigerant. The sheets 31 and 32 are brazed or welded together and have downturned flanges 33 which are secured to the side walls of the U-shaped part 11 above the bottom of the part by rivets 34 as best shown in Figure 1.

The flute 32 in the bottom sheet 31 of the shelf receives the tube 24 leading to the flute 23, in one enlarged end 32a thereof. The other enlarged end 32b of the flute 32 receives a tube 35 extending around the rear end of the U-shaped part 11 to the laterally extending plate part 13. Refrigerant thus flows from the plate part 13 through the duct in the flute 32, thence through the tube 24 into the duct provided in the flute 23.

The laterally extending plate portion 13 has the same construction as the shelf part 12 but is used in inverted position. The parts 12 and 13 are thus adapted to be made on the same forming dies and therefore only one set of dies is needed for both parts. As shown best in Figure 2, the plate part 13 has a top wall 31 which is the bottom wall of the shelf part 12. Thus the part 13 is in inverted relation to the part 12. The top wall 31 has the identical flute 32 therein with the enlarged end 32b receiving the upper end of the tube 35 and with the other enlarged end 32a receiving a refrigerant supply tube 36.

The flange 26 on one leg of the U-shaped part 11 receives one marginal edge portion of the plate part 13 thereon. This marginal portion is secured to the flange in any suitable manner such as with rivets 37.

Both this flange 26 and the marginal end portion of the plate part are apertured as at 38, and the other flange 26 is similarly apertured to provide holes for supporting bolts or lugs to suspend the unit from the top wall of a refrigerator cabinet. The plate part 13 can have the other marginal edge portion apertured as at 39 to receive supporting bolts or lugs.

As shown in Figure 4 the plate part 13 is converted into the shelf part 12 by merely trimming off the marginal edge portion 40 thereof which normally fits on the flange 26 of the U-shaped part and by turning up the flanges 33. The shelf 12 shown in Figure 5 is thus readily made from the plate part 13 shown in Figure 4. In some instances it may not be necessary to trim off a marginal portion 40 of the plate 13 provided that the width of the U-shaped part is not materially less than the length of the plate.

The plate part serves either as a cooling wall for the main interior of the refrigerator cabinet or as a refrigerated top wall of a frozen food com-

partment which can be built under the wall 13 and alongside of the U-part 11.

The refrigerant supplied through the tube 36 first passes through the duct in the flute 32 of the wall part 13 and then circulates through the tube 35 into the duct of the shelf part 12. After circulating through the duct in the shelf the refrigerant flows through the tube 24 into the duct provided in the inlet manifold flute 23 of the U-shaped part 11. Refrigerant is distributed by this inlet duct into the circulating ducts of the flutes 16. The refrigerant is discharged from these ducts into the lower headers 17 in each side wall of the U-shaped part. The spent refrigerant is then drawn through the passageways 18 into the upper headers 18 from which it is removed through the spent refrigerant duct provided by the flute 20. This duct communicates with the duct in the flute 21 and the spent refrigerant is thus discharged out of the entire unit 10 through the suction outlet tube 22.

From the above descriptions it will be understood that this invention deals with U-shaped sheet metal evaporator units having refrigerated shelves spanning the legs of the U and having laterally extending refrigerated plates on at least one leg of the U. An important feature of the invention resides in the use of identical constructions for both the refrigerated plate and the refrigerated shelf so that separate forming apparatus for the parts is not necessary. The plate wall is readily converted into the shelf by merely turning down flanges on marginal end portions thereof and, if necessary, by merely trimming off one of the marginal end portions to make the plate conform with the width of the U-shaped part.

I claim as my invention:

1. A sheet metal evaporator unit comprising a U-shaped part defining a sharp freezing chamber, a refrigerated shelf bridging the legs of the U-shaped part, and a laterally extending refrigerated plate mounted on one leg of the U-shaped part and extending laterally outward therefrom, said flat plate and said shelf having substantially identical constructions.

2. A sheet metal evaporator unit including a U-shaped part having side walls with horizontally flanged upper ends, a shelf part spanning the side walls in spaced relation above the bottom of the part, a refrigerated flat plate extending outwardly from the upper end of said U-shaped part and having a marginal end portion thereof secured to a horizontal flange of the U-shaped part.

3. A sheet metal evaporator unit including a U-shaped refrigerated part and a laterally extending flat wall refrigerated part, said U-shaped part having a substantially horizontal flange on the upper end of a side wall thereof and means securing a marginal end of said flat wall part to said flange.

4. A heat exchanger comprising a sheet metal part having side walls and a bottom defining fluid passageways therebetween, two substantially identical wall parts, each defining a refrigerant flow passageway, one of said wall parts bridging the side walls of the first mentioned part, the other of said wall parts extending laterally outward from one of the side walls of said first mentioned part, and means connecting the passageways of all of said parts.

5. A sheet metal U-shaped evaporator unit comprising a first pair of secured-together continuous metal sheets defining the side walls

and bottom of a sharp freezing chamber, said first pair of sheets defining therebetween a plurality of refrigerant circulating ducts, a refrigerant distributing manifold duct communicating therewith and an exhaust duct for spent refrigerant, a second pair of secured-together contiguous metal sheets in said sharp freezing chamber spanning the side walls of the U and defining a refrigerant duct, a third pair of secured-together contiguous metal sheets extending laterally from a side wall of the U secured to the top end of said side wall and defining a refrigerant duct, a refrigerant supply tube communicating with an end of the duct in said third pair of sheets remote from the sharp freezing chamber, a first connecting tube joining the other end of said duct in said third pair of sheets with the adjacent end of the duct in said second pair of sheets, and a second connecting tube joining the opposite end of the duct in said second pair of sheets with the manifold duct in said first pair of sheets whereby a single inlet and a single outlet connection serve to flow refrigerant through all of said ducts and tubes.

6. The method of making a U-shaped evaporator unit with a refrigerated shelf and a laterally extending refrigerated wall which comprises forming a sheet metal U-shaped evaporator part, forming two sets of embossed secured-together contiguous metal plates each providing a refrigerant flow passageway therethrough, securing one of said sets of plates on a side wall of the U-shaped part to support the set in laterally extending relation from said part, turning up flanges on the other of said sets of plates and securing said flanges to the side walls of the U-

shaped part for providing a shelf in the U-shaped part.

7. The method of forming a U-shaped sheet metal evaporator unit with a laterally extending refrigerated wall and a refrigerated shelf in the sharp freezing chamber defined by the U-shaped part which comprises providing a U-shaped sheet metal evaporator part, forming two substantially identical sets of embossed secured-together metal plates, attaching one set to a side wall of the U-shaped part for extending laterally therefrom in cantilever fashion, bending flanges on opposed marginal end portions of the other set and securing said flanges to the side walls of the U-shaped part for forming a shelf spanning the legs of the U-shaped part.
8. A sheet metal evaporator unit comprising a U-shaped part composed of embossed secured-together contiguous metal sheets defining a sharp freezing chamber and a refrigerant distributing duct, two substantially identical wall parts each composed of secured-together metal plates defining a refrigerant duct therebetween, means securing one of said wall parts to the U-shaped part in the sharp freezing chamber defined thereby to form a shelf in the chamber, means connecting the other of said wall parts to a side wall of the U-shaped part to extend laterally away from the U-shaped part, a conduit connecting the refrigerant distributing duct with the refrigerant duct in the part constituting the shelf, and a second conduit connecting said last mentioned duct with the refrigerant duct in the wall part extending laterally from the U-shaped part.

FREDERICK A. SMITH.
